tion of Ohio

(Cl. D56—2)

The figure is a perspective view of an organ console showing my new design.

The dominant features of my design reside in the portions shown in solid lines in the drawing, the conventional manuals being continuous across the key board as indicated by the dot-dash lines. The side of the organ not shown is the same as the side shown excepting the absence of the grille at the side bottom of the figure.

I claim:

The ornamental design for an organ console, sub-
stantially as shown and described.
